UNITED STATES PATENT OFFICE.

DAVID R. JENKINS, OF OAKLAND, CALIFORNIA.

WINDOW-SASH TIGHTENER FOR VEHICLE-TOPS.

1,401,606.

Specification of Letters Patent. Patented Dec. 27, 1921.

Application filed August 4, 1920. Serial No. 401,091.

To all whom it may concern:

Be it known that I, DAVID R. JENKINS, a citizen of the United States, residing at Oakland, in the county of Alameda and 5 State of California, have invented certain new and useful Improvements in Window-Sash Tighteners for Vehicle-Tops, of which the following is a specification.

My invention relates to means for automatically tightening sliding window sashes, and is particularly adapted for the sashes of vehicle tops, although it may be applied to any other form of sliding window.

In vehicle tops having horizontally sliding window sashes, the sashes must be loose enough in their guides to slide freely and easily. However, when so fitted, such sashes have a tendency to rattle, especially when slightly worn, on account of the violent and 10 constant jarring to which they are subjected, and moreover, when the vehicle is ascending or descending a steep grade, or when it starts or stops suddenly, the freely moving windows are very often shifted by the effect of 20 their own weight and inertia.

The object of my present invention, therefore, is to provide means for automatically tightening such a window at either end of its travel, without interfering with its free 30 movement between such positions, and I accomplish this by the use of simple and inexpensive devices which do not appreciably increase the weight of the window nor detract from its appearance.

With this in view, my invention will now be described with reference to the accompanying drawings, wherein—

Figure 1 is a side elevation of a vehicle top having sliding window sashes of a type 40 for which my device is well adapted.

Fig. 2 is a side elevation, enlarged, showing portions of a window sash and its guide equipped with my device.

Fig. 3 is a section taken in the direction 45 of the arrows on the line 3—3 of Fig. 2, and enlarged.

In Fig. 1 I have illustrated a well known type of vehicle top, indicated by the reference numeral 1, which is equipped in the 50 usual manner with sliding side windows—sashes 2 and 3 adapted to open by sliding rearwardly from their closed positions shown, into positions in transverse alignment with a stationary window 4. A portion 55 of the sash 2 is shown in Figs. 2 and 3,

it being understood that the other sash 3 of Fig. 1 is similar. Said sashes are hung from an upper guide member, shown at 5 in Figs. 2 and 3, said guide being inclosed within the top 1, as shown in dotted lines in Fig. 1.

The sash 2, Figs. 2 and 3, is secured to hook-shaped hangers 6, which slide in a longitudinal L-shaped groove or guide-way 7 formed in one side of the guide member 5. A similar guide way 8 is formed in the opposite side of said member 5 for receiving the hangers of the other sash 3, not shown in Figs. 2 and 3. It will be seen that, on account of the form of the hangers 6 and the guide way 7, said hangers are at all times 65 securely retained within said guide way, and the sash 2 is prevented from becoming misplaced with respect to its longitudinal path. The hangers 6 constitute the principal support for said sash.

In order to automatically tighten or lock the sash 2 at the ends of its longitudinal movement, i. e. in either open or closed position, I provide two clamping members or blocks 9 and 9', one positioned near each 70 end of the sash 2, preferably in the region of the hanger 6, and above and parallel with the upper edge of said sash. Said clamping blocks 9 and 9' are connected with the upper rail of the sash by pairs of parallel pivotally 75 mounted links 10 and 10' respectively. The length of said links is such that when the blocks 9 and 9' are raised into contact with the lower surface of the guide member 5, said links are nearly but not quite vertical, 80 so that the blocks will remain in such position, bearing firmly against said member 5, and securely clamping the sash, and will not be loosened by jarring. The block 9 is shown 85 in this position in Fig. 2.

At the ends of the guide member 5, and secured to the lower surface thereof, are fixed stops 11 and 11'. These stops are so positioned with respect to the path of movement of the sash 2, that, when said sash reaches either end of its path, one of the blocks 9 or 9', as the case may be, will abut against the corresponding stop 11 or 11', and will be forced upward thereby into contact with the underside of the member 5, to clamp 100 the sash.

Releasing lugs 12 and 12' are also secured to the under side of the guide member 5, and are spaced from the corresponding stop members 11 and 11' by a distance slightly 105 110

greater than the length of the blocks 9 and 9'. The function of said releasing lugs is to engage the rear ends of the blocks 9 and 9' and to force said blocks downwardly away 5 from the guide member 5 to release the sash when the same is moved away from either end position. Said lugs 12 and 12' are tapered on their rear or outer faces, to prevent engagement with the blocks 9 and 9' when 10 the sash is moved toward its locked position, and are thin enough to permit said blocks to pass under them when released.

A pair of friction blocks 13 are preferably carried on the upper rail of the sash 2, as 15 shown in Fig. 2. Said friction blocks are mounted for vertical movement upon dowel pins 14, and are pressed upwardly by spring 15, and caused to bear against the lower surface of the guide member 5 with sufficient 20 pressure to prevent chattering of the hangers 6 in the guide-way 7 when the sash is being moved or is in a partially open or closed position. The outer end portions of 25 said friction blocks are beveled, as shown, to avoid interference with the release lugs 12 and 12'.

The friction blocks 13 are so positioned relatively to the clamping blocks 9 and 9' that said clamping blocks are thereby prevented 30 from moving far enough to carry their connecting links 10 and 10' over the center, in the event that said blocks or the lower surface of the guide member 5 should become so worn as to render such movement 35 possible.

The operation of my device will be readily understood from the foregoing description. When the sash 2 is in the position shown in Fig. 2, that is, at one limit of its travel, the 40 clamping block 9 has been forced up against the under surface of the guide member 5 by its engagement with the stop 11, and the sash is firmly clamped. When said sash is moved toward the right, the clamping block 45 9 is engaged by the release lug 12, and is moved downward free of the guide member 5 and low enough to pass under said release lug 12. The sash can then be moved freely to the other, or right hand end of its path, 50 whereupon the clamping block 9' engages the stop 11' and is thereby raised into clamping engagement with the guide member 5, thus clamping the sash in that position.

55 It is to be understood that my invention has been described herein, and is herewith illustrated, in its preferred form, and that changes may be made in the form and construction of the device, within the scope of 60 the claims hereto appended, without departing in any manner from the spirit of the invention.

I claim:—

1. A window-sash tightener comprising a fixed guide; means for slidably connecting the window-sash with and spacing it from said guide; a pair of independent clamping members associated with the sash, one near each end thereof and lying in the space between the sash and guide; means pivotally connecting said clamping members with the sash adapting them to swing in relatively opposite directions to and from contact with said guide; a pair of fixed stops one near each end of the guide, with which the clamping members are respectively adapted to contact near the limits of travel of the sash, whereby said members are elevated into clamping engagement with the guide, a pair of fixed releasing lugs on the guide, one near each stop and with which the clamping members are respectively adapted to contact on the return movement of the sash from its limits, whereby said members are positively thrown down again and the sash freed, and a block carried by the sash and yieldingly pressed into frictional contact with the guide, said block being adapted to prevent the clamping members from swinging over center. 90

2. A window-sash tightener comprising a fixed guide having in its side a longitudinal L-shaped groove; correspondingly shaped hangers secured to and spacing the sash from the guide, said hangers being fitted in said groove and confined therein against lateral separation from said guide; a pair of independent clamping members associated with the sash, one near each end thereof and lying in the space between the sash and guide; means pivotally connecting said clamping members with the sash adapting them to swing in relatively opposite directions to and from contact with said guide; a pair of fixed stops one near each end of the guide, 100 with which the clamping members are respectively adapted to contact near the limits of travel of the sash, whereby said members are elevated into clamping engagement with the guide, a pair of fixed releasing lugs on the guide, one near each stop and with which the clamping members are respectively adapted to contact on the return movement of the sash from its limits, whereby said members are positively thrown down again and the sash freed, and a block carried by the sash and yieldingly pressed into frictional contact with the guide, said block being adapted to prevent the clamping members from swinging over center. 110

In testimony whereof I have signed my name to this specification.

DAVID R. JENKINS.
